UNITED STATES PATENT OFFICE.

MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

FILLING-REPLENISHING LOOM.

1,369,486.

Specification of Letters Patent. Patented Feb. 22, 1921.

Application filed December 24, 1919. Serial No. 347,105.

To all whom it may concern:

Be it known that I, MELVIN L. STONE, a citizen of the United States, residing at Lawrence, in the county of Essex and State of Massachusetts, have invented an Improvement in Filling-Replenishing Looms, of which the following description, in connection with the accompanying drawings, is a specification, like characters on the drawings 10 representing like parts.

This invention relates to filling replenishing looms, and more particularly to the means for effecting replenishment of the filling when that in the active shuttle has been substantially exhausted, but prior to 15 complete exhaustion.

It is now the ordinary practice in filling replenishing looms to provide a feeler mechanism which feels for the filling in the shuttle 20 on each detecting beat, and when it ascertains that the filling is substantially exhausted, it sets in operation a train of mechanism for effecting replenishment of filling. In some cases the feeler mechanism has measured or calipered the amount of filling remaining on the filling carrier or bobbin on 25 each detecting beat, and set in action a train of mechanism for effecting replenishment of filling when the measured amount of filling reaches a predetermined amount. In other cases the feeler mechanism has been mounted for movement longitudinally of the filling carrier or bobbin when the filling has 30 become substantially exhausted on a detecting beat, and such movement has been effected by either the forward push upon the feeler member, or by some mechanical means. In still other forms of feeler mechanism, the feeler member has been permitted to enter 35 a recess in the filling carrier or bobbin when the filling has reached a predetermined degree of exhaustion. In all these attempts to provide a feeler mechanism, the objects sought have been to minimize the amount 40 of waste remaining on the filling carrier or bobbin when it is ejected from the shuttle, and yet to retain sufficient amount of filling on the filling carrier or bobbin to prevent partial or mis-picks, and some of these previous attempts have met with considerable 45 success.

One of the objects of the present invention is to provide means for effecting replenishment of filling, which shall be ren-

dered operative for this purpose by the unwinding movement or motion of the filling when it has reached a degree of substantial exhaustion.

In carrying this feature of the invention into practical effect, the shuttle is provided 60 with a part which, when a working supply of filling is present in the shuttle, occupies what may be hereinafter known as a normal position, and which, when the filling is substantially exhausted, is moved into an abnormal 65 or different position by the unwinding motion or movement of the filling, and upon a detecting beat, effects replenishment of the filling.

The particular form of the part above 70 mentioned may be varied between wide limits, as applicant believes himself to be the first in the art to provide means on the shuttle which is positioned by the unwinding movement of the filling when it reaches 75 substantial exhaustion to effect replenishment. In the present embodiment of the invention, however, the said part takes the form of a pivoted element or dog, an end portion of which extends into the shuttle 80 chamber, and another portion of which extends toward the front side of the shuttle to actuate means for effecting replenishment 85 of filling when the finger or dog is moved into position by the unwinding motion of the filling as it is drawn from the filling carrier or bobbin within the shuttle.

Another important feature of the invention in this respect consists of a shifting weight which acts to hold the dog in its 90 normal position, that is, the position it occupies when a working supply of filling is in the shuttle, and is moved or shifted along the finger or dog when the latter is moved into its abnormal position by the unwinding 95 filling, to thereby hold the finger or dog in its abnormal position. In other words, the shifting weight serves to hold the dog either in its normal or abnormal position.

When the dog has been moved into its abnormal position, and is held by the shifting weight on a detecting beat, it coöperates with a train of mechanism to effect replenishment of filling. Another important feature of the invention consists of means for 100 returning the dog to its normal position when replenishment of filling is effected.

Other features and novel combination of

parts in addition to the above will be herein-after described in connection with the accompanying drawings which illustrate one good practical form of the invention.

5 In the drawings:—

Figure 1 is a perspective view of a shuttle containing the present invention, some of the parts being broken away for clearness of illustration;

10 Fig. 2 is a cross section showing the shuttle and associated parts containing the present invention, the dog being shown in its normal position;

15 Fig. 3 is a view similar to that of Fig. 2, showing the action of the parts on a detecting beat when the dog is in its abnormal position;

20 Fig. 4 is an enlarged detail sectional view showing one good form of digging and shifting weight for holding it in its normal or abnormal position;

25 Fig. 5 shows in perspective a part of the replenishing mechanism having the dog re-setting device associated therewith; and

25 Fig. 6 is a diagrammatic view showing the action of the filling on the dog when the filling is substantially exhausted and being drawn from the initial windings.

30 The shuttle body 1 may be of usual character and have the open bottom and top for the insertion and ejection of filling carriers or bobbins. At one end the shuttle is provided with the holding jaws 2 which engage suitable rings 3 on the head or base portion 35 4 of the bobbin or filling carrier for holding the latter and its load in the shuttle. The shuttle may also be provided with the usual automatic threading block, but as this does not constitute part of the present invention, 40 and is well known and understood, its illustration and description herein is not deemed necessary.

45 The shuttle 1 is provided with an opening 5 in its front wall, that is, the wall that is toward the front of the loom when the shuttle is in the shuttle-box, and extending longitudinally along the shuttle is the recess 6 formed in the shuttle body in which is seated the arm 7 which may be secured to 50 the shuttle body by the usual bolt or screw 8 by which the bobbin holding jaws are connected to the shuttle. Any appropriate means, however, may be employed for securing the arm 7 to the shuttle body. Opposite the opening 5 in the front wall of the shuttle, the arm 7 is provided with an inwardly extending flange 9 which may be formed integrally with the arm 7, or otherwise devised to provide a support for the 55 pivoted dog to be described.

60 Pivoted on the flange 9 at 10 is the dog or tilting member, one end portion 11 of which extends into the shuttle chamber at a point preferably opposite the service windings on the filling carrier or bob-

bin. The end 11 of the dog may be provided with a downwardly extending lip 12 which may engage the unwinding filling when it has reached a degree of substantial exhaustion, as will more fully hereinafter appear. 70 The dog has a frontwardly extending portion 13 which may constitute a bunter for engaging means connected to a train of mechanism for effecting replenishment of filling when the lay moves frontwardly on 75 a detecting beat, and the dog is operatively positioned.

75 The dog which may be identified as a whole as *a*, is provided with a shifting weight which may be effective for holding the dog either in its normal position, as indicated in Fig. 2, or in its abnormal position, as indicated in Fig. 3. The shifting weight may be variously contrived, but in the present instance of the invention, the 80 dog is provided with a chamber 14 which may contain a fluid, such, for instance, as mercury, and the chamber at its front portion may be somewhat deeper than at its rear portion, in order to more effectively 85 retain the dog in its operative position when it has been moved into such position by the unwinding motion or movement of the filling. When the dog is in its normal position, as indicated in Fig. 2, the front edge 95 portion 15 may act as a stop by engagement with the surface 16 forming the upper wall of the slot 5 in the shuttle side. A stop 17 extends from the dog, and by engagement with the side of the shuttle, as indicated in 100 Figs. 3 and 4, serves to determine the operative position of the dog when it has been tilted by the unwinding motion of the filling. From the construction thus far described, it will be understood that when a 105 working supply of filling is present on the filling carrier or bobbin, as indicated at *b* (Fig. 2), the dog *a* will be maintained in its normal position by the shifting weight carried by the dog. In its normal position, in the present instance of the invention, the inner end 11 of the dog is depressed, that is, the dog is tilted around its pivotal mounting 10 with its inner end 11 in lowered position, the consequence being that the shifting weight will automatically move toward the inner end of the dog and hold the dog in such position, as indicated in Fig. 2, during a weaving operation when a working supply of filling is in the shuttle. Should the dog 110 be tilted into its abnormal position, as indicated by Figs. 3 and 4, for instance, the shifting weight will move from the inner toward the outer end of the dog and retain it in its abnormal position with the stop 17 115 resting against the coöperating part of the shuttle body.

120 In order to move the dog from its normal to its abnormal position, the present invention contemplates utilizing the motion or 125

rotary movement of the filling about the filling carrier when the filling has reached a predetermined degree of exhaustion. In carrying this feature of the invention into 5 practical effect, the filling carrier or bobbin *c* has a series of initial windings wound thereon of greater diameter than the adjacent service windings, so that when the service windings are being withdrawn from the 10 shuttle, they will not strike the inner end portion of the dog, and consequently, the dog will remain in its normal position, as indicated in Fig. 2, while the service windings are being withdrawn from the shuttle. 15 When, however, the filling is being withdrawn from the windings of larger diameter than the service windings, the increased diameter of the circular arc described by the unwinding filling, will cause it to engage 20 the inner end of the dog and tilt the inner end upwardly, thereby moving the dog from its normal to its abnormal position, whereupon, the shifting weight automatically moves toward the outer end of the dog down 25 the inclined portion 18 into the slotted portion at the front of the dog, and consequently, the dog will be held in its abnormal position by the weight.

The initial windings of increased diameter may be placed upon a proper support 30 on the filling carrier or bobbin which, in the present instance, is constituted by the head 4 of the filling carrier *c*. That is, when the windings are first placed upon the filling carrier in the spinning frame, a series of initial windings 19 (Fig. 1) are placed upon the head or base of the bobbin before the service windings are laid upon the bobbin. When the filling is 35 being drawn from the service windings as represented at *d* (Fig. 6), the filling will move about the filling carrier or bobbin in a path indicated by the dot and broken lines in Fig. 6, and will not engage the inner end 40 of the dog. When, however, the service windings have been exhausted to a predetermined degree, and the filling is being drawn from the initial windings of larger diameter, which, in the present instance, are laid 45 upon the base or head of the bobbin, then the filling will be moved in a circular path about the bobbin or filling carrier in an arc of greater diameter, and such that the filling on its upward movement relative to the 50 dog, will engage the inner end of the dog, as indicated in Figs. 1 and 6, and move it from its normal to its abnormal position, where it will be held by the shifting weight.

Coöperating with the dog is a feeler member 55 which may be of any desired or usual character, and which, when the dog is in its normal or tilted position, as indicated in Fig. 2, does not engage the dog on each detecting beat, but which when the dog is 60 in its abnormal position, as indicated in

Fig. 3, engages the dog and is moved frontwardly thereby to actuate the train of mechanism for effecting replenishment of filling.

The feeler member may be of any usual type suitable for the intended purpose, but 70 in the present instance of the invention, the feeler member is constituted by an arm 20 pivotally mounted at 21 to a carrier 22 which is itself supported for movement toward and from the front of the loom. 75 Rising from the pivotal axis 21 of the feeler member is the lug 23 through which and the down-turned portion 24 of the feeler, passes the adjustable contact 25, the head 26 of which normally passes into the opening in the front wall of the shuttle on each detecting beat when the dog is in its normal position. When, however, the dog is in its abnormal position as hereinbefore described, the head 26 of the feeler member 80 will engage the front or bunter portion 13 of the dog and cause the feeler member 20 to be turned about its axis 21 to depress the front end thereof into position to engage a controller 27 and move it front- 85 wardly on further frontward movement of the lay to effect replenishment of filling. The construction of the feeler member 20, the controller 26 and the carrier 22 may 90 be substantially the same as in the "Draper feeler", and as shown and described in the patent to Wood and Northrup, No. 789,471, dated May 9, 1905. While the feeler member may be conveniently formed as above described, it is to be understood that the 95 invention is not restricted thereto, but may be associated with any appropriate form of feeler finger.

When the dog *a* has been moved from its 100 normal position (Fig. 2) to its abnormal position (Figs. 1 and 3) by the unwinding motion of the filling, it will be held in that 105 position by the shifting weight. Consequently, means are herein provided for returning the dog to its normal position when 110 replenishment of filling is effected. Such means may be variously contrived, but in the present instance, the usual transferrer 28, which as well understood in the art, transfers a filling carrier from a hopper 115 to the shuttle beneath when filling is to be replenished, is provided with an adjustable setting finger 29 which is so positioned that on the transfer of a fresh filling carrier to the shuttle by the transferrer, the end of the 120 setting finger 29 will engage the inner end portion 11 of the dog and tilt the dog into its normal position, whereupon, the shifting weight immediately assumes control of the dog in its new position and holds it in 125 such position.

The setting finger 29 may be connected to the transferrer as indicated in Fig. 5, and have an adjusting portion 30 whereby its action upon the dog may be controlled. 130

From the construction described it will be understood that the dog *a* is normally maintained in its normal position, as indicated in Fig. 2, by the shifting weight during the time filling is being withdrawn from the service windings on the filling carrier or bobbin. When, however, the filling is being withdrawn from the initial windings of larger diameter, the upwardly swinging movement of the filling as it unwinds, engages the inner end 11 of the dog adjacent the toe 12, and moves the dog into its abnormal position, as indicated in Figs. 1 and 3. The shifting weight then moves to the other side of the pivot of the dog and holds the dog in its abnormal position. When the lay moves forward and the shuttle is in the box at the detecting side of the loom or opposite the feeler member, the front end or bunter portion of the dog engages the feeler member and actuates it for effecting replenishment of filling. When filling replenishment is effected, the setting finger 29 resets the dog, and the position of the dog either in its normal or abnormal position is controlled by the stops which limit its swinging movement about its pivotal mounting on the shuttle.

What is claimed is:—

- 30 1. In a filling replenishing loom, the combination of the lay, a shuttle provided with a bobbin containing initial windings of filling on the head or base thereof, a dog pivotally mounted on the shuttle and extending into the shuttle chamber to be engaged and tilted by the unwinding motion of the filling when drawn from the head or base of the bobbin, a shifting weight movable to either side of the pivotal mounting 40 of the dog, and a feeler member adapted to be engaged and actuated by the dog on a detecting beat when it has been tilted by the unwinding filling to effect replenishment of filling.
- 45 2. In a filling replenishing loom, the combination of the lay, a shuttle provided with a bobbin containing initial windings of filling on the head or base thereof, a dog pivotally mounted on the shuttle and extending into the shuttle chamber to be engaged and tilted by the unwinding motion of the filling when drawn from the head or base of the bobbin, a shifting weight movable to either side of the pivotal mounting 50 of the dog, a feeler member adapted to be engaged and actuated by the dog on a detecting beat when it has been tilted by the unwinding filling to effect replenishment of filling, and means for tilting the dog in the opposite direction when replenishment of filling is effected.
- 55 3. In a filling replenishing loom, the combination of the lay, a shuttle provided with a bobbin having initial windings of filling 60 of greater diameter than the service wind-

ing adjacent thereto, a dog mounted on the shuttle and adapted to be moved from a normal to an abnormal position by the unwinding of the filling from the initial windings, and means actuated by the dog when in abnormal position on a detecting beat for effecting replenishment of filling.

4. In a filling replenishing loom, the combination of the lay, a shuttle provided with a bobbin having initial windings of filling 70 of greater diameter than the service winding adjacent thereto, a dog mounted on the shuttle and adapted to be moved from a normal to an abnormal position by the unwinding of the filling from the initial windings, 75 a shifting weight for holding the dog in normal or abnormal position, and means actuated by the dog when in abnormal position on a detecting beat for effecting replenishment of filling.

5. In a filling replenishing loom, the combination of the lay, a shuttle provided with a bobbin having initial windings of filling 80 of greater diameter than the adjacent service windings, a dog carried by the shuttle 85 and adapted to be moved from a normal to an abnormal position by the filling as it is unwound from the initial windings, a weight for holding the dog in normal position with permissive movement by the unwinding filling 90 to abnormal position, and means actuated by the dog when in abnormal position on a detecting beat for effecting replenishment of filling.

6. In a filling replenishing loom, the combination of the lay, a shuttle provided with a bobbin having initial windings of filling 95 of greater diameter than the adjacent service windings, a dog carried by the shuttle and adapted to be moved from a normal to 100 an abnormal position by the filling as it is unwound from the initial windings, a weight for holding the dog in normal position with permissive movement by the unwinding filling 105 to abnormal position, and means actuated by the dog when in abnormal position on a detecting beat for effecting replenishment of filling, and means for returning the dog to 110 normal position when replenishment of filling is effected.

7. In a filling replenishing loom, the combination of the lay and shuttle, a dog mounted on the shuttle and adapted to be moved from a normal to an abnormal position by the unwinding motion of the filling 115 when it is substantially exhausted, a weight for holding the dog in either normal or abnormal position, a bunter carried by the dog, and means actuated by the bunter for effecting replenishment of filling when the 120 dog is in abnormal position on a detecting beat.

8. In a filling replenishing loom, the combination of the lay and shuttle, a dog mounted on the shuttle and moved from an 125

inoperative to an operative position by the motion of the unwinding filling when it reaches a degree of substantial exhaustion, a weight movable along the dog for holding it in either operative or inoperative position, and means actuated by the dog when in operative position on a detecting beat for effecting replenishment of filling.

9. In a filling replenishing loom, the combination of the lay and shuttle, a dog mounted on the shuttle and moved from a normal to an abnormal position by the unwinding motion of the filling, and means actuated by the dog when in abnormal position on a detecting beat to effect replenishment of filling.

10. In a filling replenishing loom, the combination of the lay and shuttle, a dog mounted on the shuttle and moved from a normal to an abnormal position by the unwinding motion of the filling, a shifting weight for holding the dog in either normal or abnormal position, and means actuated by the dog when in abnormal position on a detecting beat to effect replenishment of filling.

11. In a filling replenishing loom, the combination of the lay and shuttle, a dog pivotally mounted on the shuttle and moved from a normal to an abnormal position by the unwinding motion of the filling when it is substantially exhausted, and means actuated by the abnormally positioned dog on a detecting beat for replenishing the filling.

12. In a filling replenishing loom, the combination of the lay and the shuttle, and means carried by the shuttle and positioned by the unwinding motion of the filling to effect replenishment thereof.

13. In a filling replenishing loom, the combination of the lay and the shuttle, and a dog carried by the shuttle and positioned by the unwinding motion of the filling to effect replenishment thereof.

14. In a filling replenishing loom, the combination of the lay and the shuttle, means carried by the shuttle and positioned by the unwinding motion of the filling to effect replenishment thereof, and a feeler member adapted to be actuated by the said

means when positioned by the unwinding filling on a detecting beat to effect replenishment of filling.

15. In a filling replenishing loom, the combination of the lay and shuttle, means mounted on the shuttle and moved from one position to another by the motion of the unwinding filling, a shifting weight for holding said means in either position, and a

feeler member adapted to be engaged and actuated by said means when in one of said

positions on a detecting beat to effect replenishment of filling.

16. In a filling replenishing loom, the combination of the lay and shuttle, a dog mounted on the shuttle and adapted to be moved from a normal to an abnormal position by the unwinding movement of the filling, means actuated by the dog when in abnormal position on a detecting beat for replenishing filling, and means for resetting the dog in its normal position when filling is replenished.

17. In a filling replenishing loom, the combination of the lay and shuttle, a dog mounted on the shuttle and adapted to be moved from a normal to an abnormal position by the unwinding movement of the filling, means actuated by the dog when in abnormal position on a detecting beat for replenishing filling, a finger actuated when filling is being replenished for engaging and resetting the dog in its normal position.

18. A filling detector comprising a shuttle, a dog mounted on the shuttle and movable from a normal to an abnormal position by the unwinding motion of the filling when it is nearly exhausted, and a shifting weight for holding the dog in either position.

19. A filling detector comprising a shuttle, a dog pivotally mounted on the shuttle and movable from a normal to an abnormal position by the filling as it is withdrawn from the filling carrier in the shuttle, and means for retaining the dog in either normal or abnormal position.

20. In a filling replenishing loom, the combination of the lay and shuttle, and means extending into the shuttle and positioned by the unwinding motion of the filling when it reaches a condition of substantial exhaustion to effect replenishment of filling.

21. In a filling replenishing loom, the combination of the lay and shuttle, and pivotally mounted means extending into the shuttle and positioned by the unwinding motion of the filling when it reaches a condition of substantial exhaustion to effect replenishment of filling.

22. A filling detector comprising a shuttle, a dog which is pivotally mounted on the shuttle and movable from a normal to an abnormal position by the filling as it is withdrawn from the shuttle, and a fluid shifting weight for holding the dog in either a normal or abnormal position.

In testimony whereof, I have signed my name to this specification.

MELVIN L. STONE.
